WILLIAM FINALY AND WILLIAM A. HANDELMAN, OF BRIDGEPORT, CONNECTICUT.

EXTENSION BED-SPRING.

1,280,695.

Specification of Letters Patent.

Patented Oct. 8, 1918.

Application filed February 9, 1918. Serial No. 216,162.

To all whom it may concern:

Be it known that we, (1,) WILLIAM FINALY and (2,) WILLIAM A. HANDELMAN, citizens of the United States, residing at (1,) 174 5 Orland St., Bridgeport, (2,) 310 North Washington Ave., Bridgeport, county of Fairfield, State of Connecticut, have invented an Improvement in Extension Bed-Springs, of which the following is a specification.

This invention has for its object to provide a bed spring which shall be relatively inexpensive to produce, the normal width of which shall correspond with a single bedstead of standard size, and which may be extended to three-quarter size, or to full size. So that, in fact, a single bedstead when equipped with one of our novel extension bed springs is all that is required to provide the 20 sleeping accommodation of a bed of any size up to full standard size, or if it is desirable our novel bed spring may be adjusted to fit a three quarter bedstead or a bedstead of any size from single up to the full standard 25 size.

In other words, our novel bed spring provides all the advantages of an extension bedstead or a couch bed at very much less expense. It is of especial advantage in small 30 rooms in connection with a single bedstead and enables the owner at any time to provide accommodation for an unexpected guest.

With these and other objects in view, we have devised the novel extension bed spring 35 of which the following description in connection with the accompanying drawing is a specification, reference characters being used to indicate the several parts.

Figure 1 is a perspective view illustrating our novel bed spring closed to the width 40 of a single bedstead.

Fig. 2 a similar view showing it extended to give greater width;

Fig. 3 a detail elevation on an enlarged 45 scale of one end of our novel bed springs;

Fig. 4 a detail sectional view on an enlarged scale on the line 4—4 in Fig. 1, and

Fig. 5 is a detail elevation of the inner side of the frame of the extension showing 50 one of the legs and the retaining spring.

The frame consists simply of two transverse angle strips indicated by 10 and 11, two brackets 12, secured to each angle strip near the ends thereof, and longitudinal tie 55 bars 13 (tubes in practice), the ends of which are seated in hubs 14 on the respective angle

strips. Each bracket is provided with an outwardly extending lug 15 adapted to rest on the side rail of a bedstead (not shown) these brackets serving as supports for the 60 spring as a whole. The ends of the wire mattress support, indicated by 16, are attached to the inner edges of the horizontal portions of the angle strips.

The extension comprises end angle strips 65 17 and 18 which are connected by a front angle strip 19. 20 denotes brackets rigidly secured to the inner sides of angle strips 17 and 18 near their ends, each bracket being provided with a hub 21 in which the end of a 70 longitudinal tie bar 22 is seated.

Angle strips 17 and 18 slide within angle strips 10 and 11, compare Figs. 1 and 2. The inner ends of angle strips 17 and 18 are provided with hooked lugs 23 which are 75 adapted to slide in slots 24 in angle strips 10 and 11. These lugs support the inner side of the extension and, by engagement with the outer ends of the slots, serve as stops to limit the outward movement of the 80 extension. In addition to these lugs, angle strips 17 and 18 are supported by webs 25 on brackets 12. The extension is provided with a mattress support 26, similar to mattress support 16, with a pillow support 27, which is adapted to fold down out of the way when not in use, with a hand piece 28, for convenience in operation, and with pivoted legs 29, which are adapted to fold upward into engagement with front angle strip 90 95 19 when not in use. These legs for convenience and cheapness are made of angle strips and have shoulders 30 adapted to engage the under side of the front angle strip to prevent further movement when swung downward to operative position. Each leg is provided with a spring 31, one end of which is connected to the leg at a distance from its pivotal point and the other end to the inner side of the front angle strip. It should be 100 noted, see Fig. 5, that the connection of the spring to the angle strip is above the pivotal point of the leg thereto, so that when the legs are not in use, as in Fig. 5, the springs will act to retain them out of operative position, and when swung into operative position, as in Fig. 2, the springs will swing downward past the pivotal points of the legs to the front angle strip and will act to retain the legs in that position. The 105 110 operation will be obvious from the drawing. Our novel bed spring may of course be made

of any size, but ordinarily will be made to fit a single bedstead of standard size, the lugs 15 upon the spring resting upon the side rails of the bedstead, not shown. When additional sleeping accommodation is required, the extension is simply drawn out, as in Fig. 2, and the legs swing downward to rest upon the floor, so that the spring as a whole is just as solidly supported in its extended position as when retracted. After use it is simply necessary to swing the pillow support downward and the legs upward and slide the extension back to place, it being unnecessary to disturb the frame in any way in drawing the extension outward or returning it to place.

Having thus described our invention, we claim:

1. A bed spring of the character described comprising a main frame having end bars formed of angle strips connected by tie bars, said angle strips being provided with means for removably engaging the side rails of a bedstead, an extension having end bars formed of angle strips slidably engaging the end bars of the main frame and having means whereby its inner side is supported by the main frame, when the parts are in extended relation, and means for supporting the outer side of the extension when it is drawn out from the main frame.

2. A bed spring of the character described comprising a main frame provided with depending brackets having supporting lugs shaped to removably engage the side rails of a bedstead, a slidible extension having a telescoping engagement with said main frame and having means whereby its inner side is supported by the main frame when the parts are in extended relation, and legs for supporting the outer side of the extension when it is drawn out from the main frame.

3. A bed spring of the character described comprising a main frame provided with depending brackets having supporting means for removably engaging the side rails of a bedstead, a slidible extension having a telescoping engagement with the main frame and having means whereby its inner side is supported by the main frame when the parts are in extended relation, said brackets being provided with webs for additionally sup-

porting said extension, and legs for supporting the outer side of the extension when it is drawn out from the main frame.

4. A bed spring of the character described comprising a main frame provided with supporting means for removably engaging the side rails of a bedstead, a slidible extension having a telescoping engagement with the main frame and having means whereby its inner side is supported, said supporting means also acting to limit outward movement of said extension, and means for supporting the outer side of the extension when it is drawn out from the frame.

5. A bed spring comprising a frame formed from angle strips and tie bars, said angle strips having longitudinal slots, and an extension adapted to slide within the angle strips and having lugs engaging the slots, whereby the inner side of the extension is supported and its outward movement is limited.

6. A bed spring comprising a frame having slots, brackets secured to said frame and having lugs adapted to engage the side rails of a bedstead, and webs, and an extension having lugs engaging the slots and adapted to slide on the webs.

7. A bed spring comprising a frame and an extension formed from angle strips and tie bars, the angle strips of the frame having longitudinal slots and the angle strips of the extension having lugs engaging said slots, and the extension being adapted to slide within the frame and having pivoted legs which support the front side thereof.

8. A bed spring comprising a frame consisting of angle strips having brackets secured thereto and tie bars extending between the brackets, said brackets being provided with lugs adapted to engage the side rails of a bedstead and with webs, and an extension having angle strips adapted to slide within the angle strips of the frame, the angle strips of the frame being provided with longitudinal slots and the angle strips of the extension with lugs engaging said slots, and the front of the extension sliding on the webs.

In testimony whereof we affix our signatures.

WILLIAM FINALY.

WILLIAM A. HANDELMAN.
